[57] CLAIM

The ornamental design for an exercise apparatus having single tower and support, as shown and described.

DESCRIPTION

FIG. 1 is a front perspective view of the exercise apparatus having a single tower and support showing my design; FIG. 2 is a left side elevational view thereof, wherein the right side elevational view is a mirror image thereof; FIG. 3 is a front view of the design of FIG. 1; FIG. 4 is a rear view of the design of FIG. 1; FIG. 5 is a top view of the design of FIG. 1; and, FIG. 6 is a bottom view of the design of FIG. 1. The broken line portions of the drawing disclosure are for illustrative purposes only and form no part of the claimed design.
